APPARATUS FOR APPLYING CEMENTITIOUS LININGS TO INNER WALL SURFACES OF LIQUID-HOLDING RECEPTACLES

Maurel G. Burwell, Columbus, Ohio, assignor to Century Tank Manufacturing Company, Columbus, Ohio, a corporation of Ohio

Application March 31, 1951, Serial No. 218,628

2 Claims. (Cl. 118—55)

1

This invention relates to apparatus for applying cementitious protective linings to the inner surfaces of receptacles, particularly cylindrical receptacles adapted for the reception of heated liquids, such as the hot water holding tanks, drums or boilers of residential hot water supplying systems.

Hot water tanks of cylindrical configuration having vertical side walls joined by rounded end members are now quite commonly lined with corrosion-resistant materials, such as cement, glass, enamels, and the like, to protect the inner metallic surfaces of such tanks or boilers from direct contact with water, or other liquids introduced therein. Primarily, this is done in order to prevent corrosion and rusting of such tanks, and the consequent undesirable contamination of the heated water with rust deposits or the like, the practice serving to prolong the life and usefulness of such tanks.

Considerable difficulty, however, has been encountered in the manner of effectively distributing the lining materials over all inner surfaces of such tanks or receptacles. Heretofore, the operation has been comparatively costly, slow and laborious to perform. Also, the relatively fragile nature of the inner lining produced by such an operation causes the same quite easily to become cracked or broken during shipment, handling, or use of the tanks. Again, the lining may be injured when the outer surface of a tank carrying the same is subjected to severe impact forces or sharp blows. Such lined tanks have also been found to be defective as a result of the shrinkage of the cementitious inner lining material following initial application thereof to the inner wall surfaces of the tank, and during curing of the applied cementitious mix. Such shrinkage causes the inner lining to separate in part, at least, from the inner surfaces of the metallic tank structure, thus allowing the lining to become easily broken or cracked, and incapable of withstanding the normal pressures exerted by water or other liquids introduced therein particularly when such pressures are of sufficient magnitude to provide for forced expulsion of the liquids from the tanks or receptacles.

An object of the present invention, therefore, is to provide novel apparatus by which a cementitious lining may be quickly and effectively applied to the inner surfaces of an enclosed tank, or other liquid-holding receptacle, the operation of the apparatus being such as to insure the placement and retention of the lining in association with the full area of such inner surfaces.

Another object of the invention is to provide a lining machine which produces simultaneously rotation of a tank or other receptacle about its major longitudinal axis when a fluid cementitious mix is introduced therein, whereby to cause uniform spreading of the solid constituents of the

2

mix in a protective manner over the full area of the inner surfaces of the tank or receptacle.

It is another object of the invention to provide a machine of this category wherein the drum or receptacle may be simultaneously rotated about its principal longitudinal axis and, in addition, tilted back and forth from one end thereof to the other in an oscillatory manner, whereby to further insure uniform distribution of the fluid lining-forming composition over the full inner surface area of such tanks or receptacles.

Another object of the invention is to provide a machine for lining cylindrical tanks with cementitious compositions wherein the machine provides for both axial rotation and longitudinal oscillation of a drum or receptacle undergoing lining, and, concomitantly therewith, to provide vibration or similar means for delivering rapidly executed impact forces operating on the exterior wall surfaces of the drum undergoing lining, whereby to cause the lining to adhere in a dense, compact, and permanent union with the inner surfaces of the drum or receptacle.

It is an additional object of the invention to provide a machine of the character indicated, wherein the successive and simultaneous operations indicated may be carried out while the drum undergoing lining occupies a given position on the supporting bed of the machine, the construction of the machine avoiding the necessity of transferring the drum from one machine bed to another.

The present invention accordingly consists in the provision of a machine comprising a stationary frame on which is supported for oscillatory movement about a substantially horizontal axis a drum-mounting bed, the latter carrying at one end thereof a motor-driven rotary head spindle, and at the other end thereof, and in axial alignment with the head spindle, a tail spindle, the said spindles serving to hold and clamp between the same, for rotation in unison with the head spindle, the opposite ends of a cylindrical drum or receptacle to be lined with a cementitious compound. Further, the invention consists in means provided in connection with the bed for imparting high and low speed rotation to the head spindle and a drum or receptacle mounted in connection therewith, whereby to cause high or low speed rotation of the drum about its primary longitudinal axis; also, the invention consists in a machine of this character in which a clutch controlled power-driven instrumentality is provided for effecting oscillation of the spindle-carrying bed about a horizontal axis, so that the drum undergoing lining, and carried by the spindles of the bed, will be tilted back and forth from one end thereof to the other during rotation of the drum about its principal axis.

Additionally, the invention consists in a ma-

chine of the character set forth wherein the oscillatory bed of the machine is provided with a motor-driven shaft carrying a plurality of centrifugally responsive pivotally mounted impact devices, the latter being so arranged that, upon rotation of the shaft carrying the same, the said impact devices strike the peripheral surface of an associated revolving drum in a manner producing compaction of the cementitious lining formed within the drum and the permanent adherence of the lining with the drum walls.

The invention further consists in the provision of a machine for lining the interior of metallic drums which is characterized by its simplicity, ease of control, and the rapidity with which the lining operations may be carried out.

For a further understanding of the invention, reference is to be had to the following description and the accompanying drawings, wherein:

Fig. 1 is a view partly in vertical section, disclosing a machine for producing cementitious linings in metallic drums and formed in accordance with the present invention;

Fig. 2 is a vertical transverse sectional view taken through the machine on the plane indicated by the line 2—2 of Fig. 1;

Fig. 3 is a fragmentary top plan view of the machine.

Referring more particularly to the drawings, the numeral 1 designates the frame of my improved lining-producing machine. The frame in this instance is formed to include vertically positioned transversely spaced leg-forming side members 2, the latter being united at intervals by transversely extending stationary beams 3 which form component parts of the frame 1, producing a stable upright structure.

Carried by the side members 2 are horizontally disposed trunnions 4. Supported for rocking movement by these trunnions is an oscillatory bed plate 5. The bed plate is formed to rotatably support a cylindrical metallic drum of the type indicated at 6. Such drums are commonly used in hot water heating systems and comprise the customary cylindrical metallic shell of substantially uniform cross-sectional area throughout its length, the ends of the drum being closed by upper and lower heads indicated at 7 and 8, respectively. The head 7 is formed, as usual, with pipe-receiving openings 9, and the side of the drum is equipped with a removable plug as indicated at 10. The drum is adapted to be removably positioned on the bed plate in a manner permitting rotation of the drum about its major longitudinal axis, and also to enable the drum to be tilted vertically by turning movement about the axis afforded through the horizontal trunnions 4, whereby lining material in a substantially fluidic state, and positioned in the drum, will be caused to contact uniformly all the inner surfaces of the drum, coating such surfaces with the lining material.

To removably support the drum 6 on the bed plate, the latter is provided at one end with a rotary head spindle 11, and at its opposite end with a rotary tail spindle 12. The head spindle preferably comprises a disk 13 from which project a pair of spaced studs 14, the latter being loosely received in the pipe receiving openings 9 formed in the head 7 of the drum 6, whereby to effect the support of the normally upper end of the drum in connection with the head spindle and to provide for the rotation of the drum in unison with said last-named spindle.

Further, the head spindle 11 provides a driven shaft 15 on which the disk 13 is mounted. This shaft is carried by a gear housing 16. Within the housing, suitable gearing, not shown, is provided which is driven by the electric motor or the equivalent thereof, shown at 17. Preferably included in the housing 16 is a rheostat, controlled by the operation of the manually operated handle 18, by which the speed of the motor 17 may be varied, whereby to impart relatively high speed rotation to the drum or low speed, depending upon the control conditions desired, as will be hereinafter more fully explained. It will be understood that the motor 17 and the gear housing 16 are suitably supported on the forward or head end of the bed plate, and move in unison therewith, as indicated by full and dotted lines in Fig. 1 of the drawings.

The tail spindle 12 comprises a swiveled rotatable disk 19 which is mounted for rotation on the forward end of a longitudinally adjustable screw shaft 20, the shaft being supported in connection with a threaded journal member 21 carried by the rear or tail end of the bed plate. The rear end of the shaft 20 is equipped with a hand wheel 22 by which the screw shaft may be rotated to bring the swiveled disk 19 into and out of engagement with the axial portion of the lower head 8 of the drum 6. By this construction, the head end of the drum positively receives and maintains the studs 14, openings 9 and drum heads 7, supporting the drum for rotation about its major longitudinal axis and enabling the drum to be driven by the motor 17 and associated gearing contained in the transmission member 16. Since the motor is of the variable speed type, the operation of the rheostat control 18 enables the drum to rotate at a desired rate of speed best adapted for securing efficient distribution of the cementitious mix over the inner surfaces of the drum.

In addition to the rotary motion imparted to the drum about its major longitudinal axis, the said drum is also oscillated by rocking the bed plate about its trunnions 4. Such rocking movement is obtained by power derived from the motor 17. Thus, the motor drives through the transmission 16 a horizontal shaft 23. Slidably keyed to the shaft 23 is the sliding collar 24 of a jaw clutch, the collar 24 engaging with a complementary collar 25 which is fixed to a shaft 26, the latter being disposed in alignment with the shaft or sleeve 23. The shaft 26 extends into a casing 27 secured to and depending from the under side of the bed plate 5. Within the casing 27, the shaft 26 is provided with a worm gear 28 which meshes with a worm gear 29, the latter being fixed to a shaft 30 which carries a disk shown at 31. Eccentrically connected at one side of this disk by a wrist pin shown at 32 is the upper end of a fixed pitman rod 33, the lower end of said rod being pivotally mounted as at 34 in connection with the base of the machine, either as a part of the frame 1 or on the floor 35.

It will be seen that as the disk 31 is rotated, the pitman rod 33 pivotally connected therewith produces oscillatory movement of the bed plate and the motor-driven drum positioned thereon, the drive serving to rock the drum back and forth about a horizontal axis, whereby a fluidic lining-forming mix positioned in the drum is caused to contact all the inner surfaces of the drum while the latter is being so rotated and tilted.

Another feature of the present invention re-

sides in providing the bed plate with a shaft 36 which is journaled for rotation in adjacent and parallel relationship to one side of a drum 6 when the latter is operatively positioned on the machine. The shaft 36 has the forward end thereof arranged in the gear housing 16 and the opposite end thereof suitably supported for rotation in a bearing bracket indicated at 37. Carried by the shaft 36 at closely spaced longitudinal intervals are disks 38, and to each of these disks there is pivoted as at 39 the inner ends of a pair of impact-producing arms 40, the latter swing about the pivots 39 so that their outer ends may be brought into striking contact at desired intervals with the drum. The rotary flailing arms 40 are arranged to strike the outer surface of the tank body along a line extending substantially throughout the length of the tank, and at relatively closely spaced intervals.

In the operation of the machine, a cementitious mix is first introduced in desired quantity into a drum rotatably supported on the oscillatory bed of the machine. The tank is first rotated for a short period of time, for example, approximately 5 to 8 seconds before subjecting the same to vibration. Such rotation permits the cementitious lining or aggregate material to be forcibly deposited in a uniform layer against the inner wall of the tank body prior to vibration. The flailing arms are operated through the rotation of the shaft 36, imparting relatively high speed vibrations to the tank, which vibrations serve to compact and densify the cementitious mix in layer form against the inner wall surfaces of the drum. After a predetermined spinning and vibrating cycle, the tank is permitted to come to rest. At this time, the plug 10 in the tank body is removed to permit excess water, originally contained in or expressed from the cementitious mix during the initial spinning and vibrating cycle, to drain from the interior of the tank. Preferably, after such drainage, the plug or spud 10 is replaced and a second spinning and vibrating cycle is commenced and continued for another period of time, for example, approximately 15 seconds. At the end of the second spinning and vibrating cycle, the aggregate mix usually is completely cured, this being due to the removal of the excess water as well as the chemical nature of the mix itself. Upon first introducing the cementing mix into the tank through the opening 10 and sealing the same therein, the drum is rotated slowly while the bed plate is being tilted back and forth. The speed of rotation may then be increased, and the back and forth tilting movement suspended.

Certain preferred methods for carrying out the present invention have been set forth in my co-pending application, Serial No. 216,174, filed March 17, 1951, of which this application forms a continuation-in-part.

It will be observed that all the handling operations are effected while the drum is retained in a supported position on the bed plate. It is not necessary to transfer the drum from one machine to another in imparting the desired forces thereto. Preferably, while the lining-forming operations are taking place, the exterior of the drum may be sprayed with a paint or enamel to impart a finish-producing exterior coating thereto. When removed from the machine, the drum comprises an internally lined and completed commercial product on which no further manufacturing or processing steps are required.

I claim:

1. In a machine for applying a cementitious lining to the interior surfaces of a cylindrical tank having end closures; a bed frame; a pair of rotary tank-supporting members carried in longitudinally spaced relation on said frame and engageable with the end closures of a tank for supporting the latter for rotation about its longitudinal axis; means carried by said frame and drivingly connected with one of said tank-supporting members for imparting high speed rotation to said one of said members and a tank supported between said members, whereby to centrifugally deposit a cementitious mix introduced within the tank uniformly over the inner surfaces thereof; shaft means journaled on said frame and disposed in adjacent, parallel, coextensive relation to the outer side surface of a tank supported between said members; means drivingly connected with said shaft means for imparting axial rotation thereto during rotation of the tank; and a plurality of flailing devices carried at longitudinally spaced intervals along said shaft means and engageable with the outer side surfaces of the tank during rotation of said shaft means for imparting vibrational forces to the tank substantially throughout its entire length, whereby to compact a cementitious mix centrifugally deposited against the inner surfaces of the tank during high speed rotation of the latter.
2. Apparatus for applying a cementitious lining to the inner surfaces of a hot water tank comprising a bed frame; a pair of bolsters rigidly carried in longitudinally spaced relation on said frame; a pair of rotary tank-supporting members carried by said bolsters and engageable with a tank at the respective ends thereof for supporting the tank for rotation about its longitudinal axis; means connected with one of said members for adjusting the longitudinal spacing thereof with respect to the other of said members; motor means carried by said frame; drive means connected between said motor means and one of said tank-supporting members for imparting higher speed rotation to said one of said members and a tank supported between said members, whereby to cause a cementitious mix introduced within the tank to be centrifugally deposited in a uniform layer over the inner side surface of the tank; shaft means journaled on said frame in adjacent, parallel, coextensive relation to the outer side surface of a tank supported between said members; means drivingly connecting said shaft means with said motor means for imparting axial rotation to said shaft means during rotation of a tank carried between said members; and a plurality of knocker arms pivotally carried by said shaft means at longitudinally spaced intervals therealong and engageable with the outer side surface of a tank carried between said members for imparting vibrational forces to the tank throughout substantially its entire length during rotation thereof, and thereby compacting a cementitious mix deposited against the inner side wall of the tank.

MAUREL G. BURWELL.
